J. J. SLEEPER,
DISH WASHING MACHINE.
APPLICATION FILED DEC. 10, 1913.

1,123,604.

Patented Jan. 5, 1915.

UNITED STATES PATENT OFFICE.

JOSEPH J. SLEEPER, OF MOORES, PENNSYLVANIA.

DISH-WASHING MACHINE.

1,123,604.

Specification of Letters Patent.

Patented Jan. 5, 1915.

Application filed December 10, 1913. Serial No. 805,688.

To all whom it may concern:

Be it known that I, JOSEPH J. SLEEPER, a citizen of the United States, residing at Moores, in the county of Delaware and State 5 of Pennsylvania, have invented certain new and useful Improvements in Dish-Washing Machines, of which the following is a specification.

My invention relates to improvements in 10 dish washing machines, an object of the invention being to provide an improved construction of agitator movable in a well in the base of a dish containing receptacle, and adapted when moved in the well to throw 15 the water in various directions to thoroughly wash the dishes.

A further object is to provide a washing 20 machine and improved construction of agitator with means for alternately moving the same in different directions and imparting to the water different movements during the 25 operation of the agitator to thoroughly cleanse the dishes.

A further object is to provide an improved 30 dish washing machine having an improved arrangement of rotary agitators in a confined receptacle, and having improved means for permitting a free communication with the outside air so as to insure normal conditions 35 within the receptacle and prevent partial vacuum or pressure which would interfere with the perfect washing of the dishes.

With these and other objects in view, the 40 invention consists in certain novel features of construction and combinations and arrangements of parts as will be more fully hereinafter described and pointed out in the claims.

45 In the accompanying drawings: Figure 1 is a view in vertical section illustrating my improvements. Fig. 2 is a view in elevation at right angles to Fig. 1 with the upper portion of the receptacle shown in section.

Fig. 3 is a view in horizontal section on the line 3—3 of Fig. 1. Fig. 4 is a top plan view. Fig. 5 is a fragmentary view in elevation showing a modified arrangement of agitators illustrating the same in connection 50 with the receptacle well, a portion of the latter being shown in section, and Fig. 6 is an enlarged view in longitudinal section on the line 6—6 of Fig. 5.

1 represents a receptacle having a well 2 55 in its bottom, said well and receptacle both

preferably of circular shape in horizontal section with the outer walls of the receptacle and well concentric, but the latter appreciably smaller in diameter than the receptacle proper so that a circular ledge 3 is 60 formed to support wire baskets 4 adapted to contain the dishes to be washed. These wire baskets are preferably composed of ordinary wire covered with fiber, cork, or any other suitable material as indicated at 5 to 65 prevent chipping the dishes and cushioning the contact of the same with the baskets. I preferably provide feet 6 to support the machine, and in the bottom of the well 2, an outlet 7 is formed having a discharge 70 pipe 8 extending at an angle therefrom and normally closed by a stopper 9.

The upper end of the receptacle 1 is closed by a removable cover 10, the latter consisting of three parts 11, 12, and 13. The intermediate portion 12 is provided with overlapping flanges 14 which are secured by bolts 15 and wing nuts 16 to the sides of the receptacle 1. The sections 11 and 13 are connected by hinges 17 with the intermediate 75 section 10, so that they may be readily moved up and down to permit access to the receptacle.

The intermediate section 12 of the cover 1 has a central bearing 18 for a vertical tubular shaft 19, and the latter having a beveled pinion 20 on its upper end meshing with a beveled drive gear 21. The gear 21 is supported upon a shaft 22 carried by brackets 23 on the intermediate section 12, and back 80 of the gear 21, I preferably locate ball bearings 24 to sustain the thrust and hold the gear up to its meshing position with pinion 20. An operating lever 25 is secured to turn with the gear 21, and is adapted to be oscillated so as to impart a rotary movement to the shaft 19, first in one direction, and then in the other as will more fully hereinafter appear. 85

The lower closed end 26 of shaft 18 has a 90 thrust bearing 27 on a pin 28 fixed in the bottom of the well 2, and to the shaft 19 near its bottom, horizontal bars 29 are rigidly secured. On these bars 29, my improved agitators 30 are secured. While the 95 invention is of course not limited to any particular manner of connecting the agitators with the shaft, I preferably provide bolts 31 as shown, nor is the invention limited to any particular number of these agi- 100 105 110

tators, as for example, in Fig. 3 I have illustrated two agitators, and in Fig. 5, four.

These agitators 30 are preferably formed of sheet metal and have deflecting surfaces 32 and 33 at an angle to each other, and at different angles relative to the bottom of the well. These surfaces 32 and 33, as well as the bottom 34 and sides 35 may be formed from a single sheet metal blank.

10 In Fig. 5, I have illustrated two pairs of agitators, and it will be observed that the outside agitators have their outer walls 36 at an angle to the side walls of the well, and it is to be understood that the above angles of the different walls of the agitators result in imparting different movements to the water in the well as will be explained.

It is to be understood that the well will contain water up to a point approximating 20 its upper end, and this is all the water there will be in the receptacle. In the bottom of the well or rather at a point slightly removed from the bottom, a wire screen 37 is located. This screen has two important 25 functions, first, it permits solid particles to pass through the screen and retards their upward movement, and secondly, the screen serves to retard the rotary movement of the water which augments the angular throw of 30 the water by the agitators.

As above stated, the shaft 18 is tubular or hollow, and this shaft communicates at its upper end with the outside air and throughout its length in the receptacle is provided 35 with perforations 38, so that the air inside the receptacle has free communication with the outside air. This prevents either pressure or partial vacuum and prevents an undesirable accumulation of soapy bubbles 40 around the dishes.

Assuming the baskets 4 to be full of dishes to be washed, and well 2 full of water which may be impregnated with soap or any cleaning composition, when the lever 25 is oscillated, shaft 18 will be revolved in one direction, and then in the opposite direction. During the first movement, the inclined surface 32 will throw the water in one direction, and on the reverse movement, the inclined surface 33 will impart a different movement to the water. The inclined outer walls 36 will also give the water an upward swirling movement, and these combined movements imparted to the water will insure a perfect cleansing of the dishes, as all parts of the dishes will be subjected to contact with the water which will be thrown with considerable force. In the normal operation of the device, these varying movements given to the water may of course be altered by changing the angles of the different surfaces, but I believe the particular shape illustrated is a preferable one because of the many different movements attained.

65 After the dishes are washed, the dirty water

may be allowed to drain off, and clear hot water supplied to the well, and the dishes thoroughly rinsed and allowed to dry.

Having thus described my invention, what I claim as new and desire to secure by Letters Patent is:

1. In a washing machine, the combination with a receptacle, of an agitator movable in the receptacle adjacent the bottom thereof and in a path concentric with the center of 75 the receptacle, said agitator having deflecting surfaces at its respective ends at an angle to each other and at different angles relative to the bottom of the receptacle, and means for moving the agitator in opposite 80 directions, substantially as described.

2. In a washing machine, the combination with a receptacle, a vertical shaft in the receptacle, and agitators connected to and movable by the shaft in a circular path adjacent the bottom of the receptacle, said agitators having at their respective ends water deflecting surfaces at an angle to each other, and means for imparting a rotary movement to the shaft first in one direction and then 90 in the other, substantially as described.

3. In a washing machine, the combination with a receptacle having a concentric well in its bottom of appreciably less diameter than the receptacle, a screen in the well 95 spaced from the bottom thereof, a rotary shaft positioned vertically in the well, agitators at opposite sides of the shaft and secured to turn therewith, said agitators having water deflecting surfaces at both ends 100 and at both sides at various angles, and means on the upper end of the receptacle for imparting a rotary movement to the shaft first in one direction and then in the other, substantially as described.

4. In a washing machine, the combination with a receptacle having a concentric well in its bottom of appreciably less diameter than the receptacle, a screen in the well spaced from the bottom thereof, a rotary 110 shaft positioned vertically in the well, agitators at opposite sides of the shaft and secured to turn therewith, said agitators having a plurality of water deflecting surfaces at various angles, said shaft tubular in form 115 communicating at its upper end with the outside air and perforated throughout its length, and means for turning the shaft in opposite directions, substantially as described.

5. In a washing machine, the combination with a receptacle having a concentric well in its bottom of appreciably less diameter than the receptacle and forming at its juncture with the receptacle, a support for a dish 125 holding tray, a vertical drive shaft in the receptacle and well, a screen in the well above the bottom thereof, agitators secured to opposite sides of the vertical shaft and having water deflecting surfaces at their 130

ends at different angles relative to each other and to the bottom of the well, and having deflecting surfaces at their sides at an angle to each other, and means for imparting rotary motion to the shaft, first in one direction and then in the other, substantially as described.

In testimony whereof I have signed my name to this specification in the presence of two subscribing witnesses.

JOSEPH J. SLEEPER.
